WALL TILE CONSTRUCTION

Robert J. Bergez, San Francisco, Calif.

Application May 4, 1937, Serial No. 140,669

1 Claim. (Cl. 72—18)

My invention relates to improvements in a wall tile construction, and it consists of the combinations, constructions and arrangements hereinafter described and claimed.

5 The usual wall tile is provided with a glazed top surface made from glass that is either sprayed or brushed onto the top of the tile and then the tile is again baked. Since this glazed surface is a different material from the body of the tile, it 10 will easily chip and this will mar the appearance of the tile. In laying the wall tile, they are placed against a cement base and the straight edges of the tile are either abutted against each other or are spaced a slight distance apart. Where the 15 tile are placed against each other, they form what is known as a tight joint. Any movement caused by the settling of the wall structure, will bring the edges of the adjacent glazed faces of the tiles against each other resulting in a chipping or 20 flaking of the glazed surface. This soon creates an unsightly appearance in the tile construction because the glazed surface has a color differing from the color of the body of the tile. Even where the color is the same, the difference is noticeable 25 between a glazed surface and chipped portions not glazed.

Where the tiles are spaced a slight distance apart to form what is known as a string joint, the space between the adjacent tiles is normally 30 filled with a white cement and this cement will become discolored by drawing the coloring matter from the gray cement that supports the bases of the tiles. It is usually the practice to fill the 35 spaces of the string joints with a white cement while the gray cement is still wet and it is for this reason that the white cement becomes discolored.

The principal object of my invention is to provide a tile construction that will overcome the 40 disadvantage of the glazed surface flaking, due to the edges of these glazed surfaces abutting one another under pressure, and which will overcome the disadvantage of causing the white cement placed in the string joints from becoming gray 45 through absorbing a portion of the coloring from the gray cement. Each tile of my invention is provided with edges that have recessed portions disposed adjacent to the glazed face of the tile. Each edge will be provided with a recess that has 50 a width substantially one-half the depth of the tile, although I do not wish to be confined to this particular dimension. The recessed portion of the edge is shallow so that the placing of two tiles 55 against each other in abutting relation will cause

these recessed portions to form a groove resembling a string joint.

In assembling my improved tiles, the lower portions of the edges disposed adjacent to the base of the tiles, are brought into abutting relation to 5 form a tight joint and the undersurface of the tile will be supported by the gray cement in the usual manner. This will provide a slight space or groove between the adjacent tiles at the glazed surfaces. The edges of the glazed surfaces will 10 therefore not abut each other, and any settling of the wall tile construction will not cause these edges to be forced against each other with the result that there will be no flaking or chipping of the glazed surfaces. Moreover the grooves 15 formed between the glazed surfaces may be filled with the white cement and this cement can not become discolored from the gray cement because the lower portions of the edges abut each other and prevent the white cement from contacting 20 with the gray cement.

Other objects and advantages will appear in the following specification, and the novel features of the device will be particularly pointed out in 25 the appended claim.

My invention is illustrated in the accompanying drawing forming a part of this application, in which

Figure 1 is a plan view of the improved tiles, shown assembled;

Figure 2 is an enlarged section along the line 2—2 of Figure 1; and

Figure 3 is an isometric view of a tile.

In carrying out my invention I provide a tile indicated generally at A and this tile may be of 35 any shape desired. In Figure 3 I show the tile as being square and as being provided with a glazed surface 1 and with a bottom surface 2 that is designed to be placed upon a supporting bed of gray cement. All four edges 3 of the tile are 40 recessed at 4 and it will be noted that the recesses extend downwardly from the glazed surface a short distance. Each recess 4 is shallow. The glazed surface is formed by either spraying or brushing liquid glass onto the top face of the 45 tile in the usual manner. The tile is then baked again and will be provided with a face differing in composition from the body of the tile. The brittleness of the glazed face causes it to chip easily.

In Figure 2, I show the tile A placed upon a 50 supporting layer of gray cement indicated at B. This cement in turn is supported by the usual wall lath construction C or other suitable construction. Figure 2 shows the edges 3 of adjacent tile abutting each other and further illustrates how the 55

recesses 4 provide a space between adjacent glazed surfaces 1 so that the tiles will appear to be constructed with a string joint between each tile rather than a tight joint. A white cement indicated at D is placed in the grooves formed by the recesses so that these grooves will be entirely filled. It will be seen from Figure 2 that the white cement is spaced from the gray cement because the edges 3 of the adjacent tile abut each other.

In Figure 1 I show a number of the tiles assembled on a wall and this figure clearly shows the glazed faces 1 of the tiles spaced from adjacent glazed faces by grooves formed from the two operating recesses 4. If desired the rear face 2 of the tile may be ribbed at 5 and these ribs will be embedded in the gray cement and thus more effectively support the tiles.

From the foregoing description of the various parts of the device, the operation thereof may be readily understood.

The tiles are placed in position on the gray cement B in the same manner as when mounting tile to make tight joints between the adjacent tiles. This tight joint between adjacent tiles will be on the back sides or bases of the tiles and will prevent the gray cement from passing between the adjacent edges of the tile. The front glazed surfaces of the tiles will be provided with grooves disposed between adjacent tiles and these grooves will extend substantially half-way down the edges of the tiles from the glazed surfaces to the bases. The grooves are filled with the white cement D, and this will give an appearance to the tile construction as though it were provided with

string joints rather than tight joints. The white cement D is separated from the gray cement B by the tight joints disposed at the rear or the bases of the tiles and therefore the gray cement will not stain the white cement.

It will be seen that with this type of tile construction that the glazed surfaces 1 can not crack or flake because these surfaces on adjacent tiles do not touch each other. The cement D in the grooves separates the glazed surfaces and this cement is known as grout. Since the grooves do not extend to the bottoms of the tiles a saving of the white cement will result. Furthermore it is possible to add the white cement to the grooves on the same day that the tile is placed on the gray cement without any fear of the white cement becoming stained.

While I have shown only the preferred form of my invention, it should be understood that various changes or modifications may be made within the scope of the appended claim without departing from the spirit of the invention.

I claim:

A wall tile construction comprising a supporting layer of cement, tiles placed against the cement with their edges abutting each other, the faces of the tiles being glazed and of less area than the bases of the tiles, whereby the edges of the faces of adjacent tiles are spaced from each other to provide grooves that bound all sides of each tile, and a cement filling the grooves and being spaced from the layer of cement that supports the tiles by the lower edges of the tile abutting the lower edges of adjacent tiles.
